Primary Examiner — Maria J. Edwards*Assistant Examiner* — Dina Michelle Hoeynck(74) *Attorney, Agent, or Firm* — Alexander Chen, Esq.(57) **CLAIM**

The ornamental design for a loupe set, as shown and described.

DESCRIPTION

FIG. 1 is a perspective top view of the left loupe of a set, with the right loupe being identical;

FIG. 2 is a perspective bottom view thereof;

FIG. 3 is a left side view thereof;

FIG. 4 is a right side view thereof;

FIG. 5 is a front view thereof;

FIG. 6 is a back view thereof;

FIG. 7 is a top view thereof;

FIG. 8 is a bottom view thereof; and,

FIG. 9 is a perspective view of the loupe set in a configuration of use.

The broken lines in the drawings depict environmental structures, used together with the article, that form no part of the claimed design.
